[57] **CLAIM**

The ornamental design for a switch operated hand set for use with traffic radar devices or the like, as shown and described.

DESCRIPTION

FIG. 1 is a front elevational view of the switch operated hand set for use with traffic radar devices or the like embodying my design;

FIG. 2 is a rear elevational view of the design shown in FIG. 1;

FIG. 3 is a left side elevational view of the design shown in FIG. 1;

FIG. 4 is a right side elevational view of the design shown in FIG. 1;

FIG. 5 is a top plan view of the design shown in FIG. 1; and

FIG. 6 is a bottom plan view of the design shown in FIG. 1.

*Fig. 1.**Fig. 2.**Fig. 3.**Fig. 4.**Fig. 5.**Fig. 6.*
